WINDOW SCRAPER HOLDER

Ronald David Carter, Leamington Spa, England, assignor to The Stanley Works, New Britain, Conn., a corporation of Connecticut

Filed Aug. 27, 1969, Ser. No. 18,879

Term of patent 14 years

Int. Cl. D7—06

U.S. Cl. D49—26

In the drawing:

FIG. 1 is a top plan view of the window scraper holder of my new design;

FIG. 2 is a left side view thereof;

FIG. 3 is a bottom plan view thereof;

FIG. 4 is a left end view thereof; and

FIG. 5 is a right end view thereof.

The broken lines representing the blade are shown for illustrative purposes only and do not form a part of the claimed design.

I claim:

The ornamental design of a window scraper holder, as shown and described.
